COPYHOLDER

Nazario Lomboy Doria, San Francisco, Calif.

Application July 12, 1940, Serial No. 345,229

3 Claims. (Cl. 120—28)

This invention relates to a copyholder designed primarily for use in connection with typewriters, one of the objects being to provide a simple, compact and efficient device of this character which can be compactly stored when not in use and which can be attached readily to a typewriter so as to support copy in position where it can be easily read while the typewriter is being operated.

10 Another object is to provide a copyholder having a copy engaging and supporting head readily shiftable into holding position or into collapsed position.

15 A still further object is to provide a copyholder which is adaptable to different makes of typewriters and in no way interferes with the manipulation of any of the typewriter parts.

20 A still further object is to provide a copyholder which includes in its construction a guide or deflector for the paper mounted in the carriage of the typewriter whereby the paper is deflected downwardly as it leaves the platen of the typewriter, thereby preventing it from assuming a position in front of the copy and obscuring it.

25 A still further object is to provide a copyholder readily adjustable to support the copy at any desired angle most suited to the user.

With the foregoing and other objects in view which will appear as the description proceeds, 30 the invention consists of certain novel details of construction and combinations of parts hereinafter more fully described and pointed out in the claims, it being understood that changes may be made in the construction and arrangement of parts without departing from the spirit 35 of the invention as claimed.

In the accompanying drawings the preferred form of the invention has been shown.

In said drawings

40 Figure 1 is a side elevation of the copyholder attached to a typewriter, the latter being illustrated by broken lines and the position of a sheet of paper while leaving the typewriter being also indicated.

45 Figure 2 is a front elevation of the device, the lower portion of the post and guide plate being broken away and the copyholder being shown by broken lines in partly collapsed position.

Figure 3 is a section on line 3—3, Figure 2. 50 Figure 4 is a rear elevation of the upper portion of the copyholder when collapsed, the upper portions of the posts and the parts in engagement therewith being in section.

55 Referring to the figures by characters of reference, 1 designates side supporting posts which

are preferably curved in the direction of their lengths and spaced apart a sufficient distance to permit their lower ends to be detachably secured to the respective sides of the back portion of a typewriter T. These posts are provided with 5 openings 2 for the reception of screws, bolts or the like whereby the posts can be attached to the typewriter. The forward edges of the posts, which are the edges nearest the typewriter, are concave in the direction of their length and joined 10 by an arcuate guide plate 3 the lower edge of which is positioned back of and slightly spaced from the typewriter T while the upper end is curved upwardly and forwardly so as to overhang the back portion of the typewriter and form a 15 deflector 4 projecting into the path of a sheet of paper S when it moves backwardly from the platen P of the typewriter. This guide plate and deflector can be made integral with the posts or can be joined thereto in any suitable manner. 20

Extending over the upper ends of the posts is a strip 5 providing along the front portion thereof, a supporting ledge 6 and projecting upwardly from this strip and back of the ledge is a flange 7. Ears 8 are extended downwardly 25 from the strip and are pivotally connected to the respective posts 1 as indicated at 9, each of these connections being in the form of a screw 10 extending loosely through the upper end of the post and having a threaded portion engaging the ear 8. The screw has a head 11 by means of which it can be turned for the purpose of binding the posts against the ears or releasing them from binding engagement. Thus the strip 5 can be adjusted angularly about the axes 30 35 of the screws 10 and thereby be brought to any desired position.

Pivotally connected to the flange 7 near each of its ends is the lower end of a pair of links 12, the pivots being indicated at 13. The links 12 40 of each pair are pivotally joined by an elbow joint shown generally at 14. Thus the links of the two pairs are free to fold downwardly into lapping relation, it being understood that the links of one pair are mounted on the front face 45 of the flange 7 while the links of the other pair are mounted on the back face of the flange, as clearly shown in Figure 1. Thus when the links are folded downwardly they will be supported on the strip 5 at opposite sides of the flange 7. 50 When the links are brought into alignment, however, the joints 14 will prevent them from moving outwardly out of alignment.

The upper ends of the two pairs of links are pivotally connected, at 15, to a cross-strip 16 55

constituting the head of the holder, the links of one pair extending in front of this head while the links of the other pair extend back of the head. A spring-controlled clip 18 is attached 5 to the front of the head at the top thereof and cooperates with the head to grip any papers which might be inserted therebetween.

Normally the head 17 is resting on the flange 1 with the links folded together at opposite sides 10 of the head and flange. This normal position of the parts has been shown in Figure 4. Assuming that the posts 1 have been attached to a typewriter as shown in Figure 1, the copyholder is brought into position for use by pulling upwardly 15 on the head 17, thereby stretching out the pairs of links until the links of each pair are brought into alignment. The upper edge of the manuscript to be copied is then inserted between head 17 and clip 18 so as to be gripped, this copy or manuscript being indicated at C. The lower edge of the copy will be supported above the ledge 6 and can bear backwardly toward the flange 1. Thereafter the strip 5 can be adjusted 20 about the axes of the bolts 9 until the copy is supported at the angle best suited to the user. The bolts 10 are then tightened so that the parts will not shift out of proper position. The sheet of paper S is inserted in the typewriter in the usual way and as it is fed therefrom it will move 25 backwardly against the deflecting portion 4 of plate 3 and be guided downwardly along said plate so that it will not obscure any of the copy being supported.

If desired, and as shown, the pivots 15 can be tightened by wing nuts so that it is thus possible to adjust the head 17 to an intermediate position with the links of each pair disposed at an angle to each other after which, by tightening the 30 pivots 15, the parts will be held against further downward movement. This arrangement makes the holder especially useful when it is desired to support a short sheet of copy at the lowest possible level above the typewriter.

45 It will be noted that this device is very simple and compact in construction, cheap to manufacture, and easy to apply. When it is not in use it can be folded into a compact structure and, when thus folded and detached from the type-

writer, can be conveniently stored in a small space.

What is claimed is:

1. A copyholder including posts spaced for attachment to the sides of the back portion of a typewriter, an arcuate guide plate connecting the posts and having an upwardly and forwardly projecting portion constituting a deflector for overhanging the back portion of a typewriter, a cross-strip connecting the upper ends of the posts and mounted for angular adjustment about an axis extending transversely through the posts, a copy supporting head, and a collapsible connection between said head and the cross-strip. 5

10 2. A copyholder including posts spaced for attachment to the sides of the back portion of a typewriter, an arcuate guide plate connecting the posts and having an upwardly and forwardly projecting portion constituting a deflector for overhanging the back portion of a typewriter, a cross-strip connecting the upper ends of the posts and mounted for angular adjustment about an axis extending transversely through the posts, a copy supporting head, and a collapsible connection 15 between said head and the cross-strip, said connection including opposed pairs of links interposed between and connected to the cross-strip and head, the links of each pair being connected by an elbow joint. 20

25 3. A copyholder including spaced posts for attachment to opposed sides of a typewriter, an arcuate guide plate connecting the posts and having an upwardly and forwardly curved portion constituting a paper deflector, a cross-strip connecting the upper ends of the posts and mounted for angular adjustment about an axis extending transversely of the posts, means for holding said strip in any position to which it might be adjusted, an upwardly extending longitudinal flange on the strip, a head, means on 30 the head for engaging and gripping manuscript, and collapsible connections between the head and the strip, said connections including opposed pairs of links, the links of each pair being joined by an elbow joint and located at opposite 35 sides respectively of the flange and of the head, said links being foldable into position on the strip and at opposite sides of the flange. 40

45 NAZARIO LOMBOY DORIA.
